UNITED STATES PATENT OFFICE.

ELEANOR BUTTERS, OF IPSWICH, ENGLAND.

COMBINATION-GARMENT FOR WOMEN.

1,356,261.

Specification of Letters Patent.

Patented Oct. 19, 1920.

Application filed November 14, 1918. Serial No. 262,577.

To all whom it may concern:

Be it known that I, ELEANOR BUTTERS, a subject of the King of Great Britain, residing at Park House, Aneaster Road, Ipswich, 5 Suffolk, England, have invented new and useful Improvements in Combination-Garments for Women, of which the following is a specification.

My invention relates to combined vests 10 and pants for women's wear, and to that class of such garment provided with an apron or flap which hangs approximately from the waist line, on the inner side of the garment, and is of such length that it will 15 practically cover the usual division between the two leg portions and will be sat upon by the wearer.

The object of my invention is to render 20 such garments more hygienic or sanitary than heretofore, and to this end my said invention consists in the application to the said apron or flap of a detachable shield or cover.

My invention will be readily understood 25 by reference to the accompanying drawing, in which:—

Fig. 2 is a similar view with the central front portion of the garment cut away.

30 In these figures a indicates the apron or flap arranged on the inner side of the back portion of the garment to cover the opening or slit, which is indicated by dotted lines at b, the said apron being of such length that the wearer will sit upon it, and 35 c is the detachable shield or cover provided according to my invention, and advantageously constructed with button holes so that it can be applied to buttons d on the garment. Or the buttons can be on the shield 40 or cover and the button holes formed in the garment or in a band or strip to which the apron or flap is fixed if it is not woven in one with the garment.

It will be understood that with this construction the cover can be changed from time to time as required.

Claim.

A combination garment for women including a drop seat arranged on the inner 50 side of the back portion of the garment, and a detachable shield substantially covering the drop seat, said garment having a slit at its rear lower part, the edges of the split portion of the garment approximately meeting without overlapping, such slit being covered by the drop seat and shield when the garment is in position on the body of the 55 wearer.

ELEANOR BUTTERS.
